HINGE

John Sunko, Elgin, Ill., assignor to Motorola, Inc.,
Chicago, Ill., a corporation of Illinois

Application September 21, 1953, Serial No. 381,172

2 Claims. (Cl. 220—31)

The present invention relates generally to hinged structures and more particularly to a receptacle for a radio receiver or the like which comprises a pair of sections hinged together in an improved and simplified manner.

It is usual in the present-day construction of radio receivers of the portable type to manufacture such receivers in a two-piece molded cabinet. The pieces are hinged at one edge and are usually held together by a suitable clasp at an opposite edge. It is most desirable to provide such a receptacle for a radio receiver or the like that lends itself readily to a molded construction and in which the two sections may be hinged together quickly and conveniently.

It is, accordingly, an object of the present invention to provide an improved hinged structure comprising a pair of casing sections hinged together in an improved and simplified manner.

Another object of the invention is to provide such an improved hinged structure that may be manufactured simply and expeditiously and without the need for heat fusing or other relatively difficult and time-consuming operations.

Another object of the invention is to provide such an improved hinged structure that lends itself readily to a molded construction.

A feature of the present invention is the provision of a hinged structure that comprises a pair of casing sections having slots formed in their adjacent edges and which are hinged together by a simple hinge pin that may be readily inserted in the slots and which has a bent-over end portion which engages a notch in one of the casing sections and holds the pin against longitudinal movement.

Another feature of the invention is the provision of such a hinged structure in which the casing sections have slots with open sides molded in their adjacent edges, and in which the sections are hinged together by a simple hinge pin retained in the slots by means of a pair of washers which also function as bearings for the sections.

The above and other features of the invention which are believed to be new are set forth with particularity in the appended claims. The invention itself, however, together with further objects and advantages thereof, may best be understood by reference to the following description when taken in conjunction with the accompanying drawing in which:

Figure 1 is a perspective view of the hinged structure of the invention;

Figure 2 is an exploded view of a portion of the structure; and

Figure 3 is another view partly in section of a portion of the structure.

The invention provides a hinged structure which comprises a first section having an edge with a pair of aligned slots formed therein and spaced along the edge. The first section has an opening therein adjacent the edge and adjacent one of the pair of slots at the end thereof remote from the other of the pair of slots. The structure also includes a second section having an edge with a slot

2

formed therein and aligned with the pair of slots mentioned above. A hinge pin is provided which extends through the pair of slots in the first section and through the slot in the second section for maintaining the sections in hinged relation. The hinge pin has a bent-over end portion extending beyond the one of the pair of slots adjacent the opening referred to above, the end portion being disposed in the opening to prevent longitudinal movement of the pin.

With reference now to the drawing, the hinged structure illustrated therein includes a first casing section 10 and a second casing section 11. The casing sections preferably are of molded construction and each has a top 12 with four integral sides 13 extending perpendicularly therefrom.

One of the sides 13 of the casing section 11 terminates in an edge having an elongated notch 14 formed herein and extending along the edge. This edge also has a pair of molded integral bent-over protuberances 15 and 16 disposed at the end of notch 14 and defining a pair of aligned slots 17 and 18 extending parallel to the edge. Slots 17 and 18 are each open along one side to facilitate the molding process, and at least slot 17 is open at its outer end for reasons to be described. The edge referred to above has a further notch 19 formed therein adjacent the outer end of slot 17.

One of the sides 13 of the molded section 10 terminates in an edge adjacent the edge of section 11 referred to previously, and that edge of section 10 has a molded integral bent-over protruding portion 20 formed therein disposed in the elongated notch 14 in section 11. The protruding portion 20 defines a slot extending parallel to and aligned with slots 17 and 18.

A hinge pin 21 extends through slots 17 and 18 in section 11 and through the aligned slots formed by portion 20, thereby maintaining the sections in hinged relation. A pair of washers 22 and 23 is mounted on the hinge pin and disposed adjacent the inner ends of slots 17 and 18. These washers function as bearings for the structure and also serve to retain pin 21 within the slots 17 and 18 by engaging the rear of notch 14.

Hinge pin 21 has a bent-over end portion 24 which extends beyond the outer end of slot 17 and which is turned into notch 19 to prevent longitudinal movement of the pin and to retain the pin in the slot.

The hinged structure may be assembled simply and conveniently in the following manner. As previously mentioned, casing sections 10 and 11, together with the protruding portions 15, 16 and 20, may be formed by usual molding techniques. The casing sections are laid open at approximately 120° with the hinge receptacle slots aligned to receive the hinge pin. Washers 22 and 23 are then dropped into position between the respective inner ends of portions 15 and 16 and the ends of portion 20. Hinge pin 21 is then inserted through slot 17, washer 23, the slot in portion 20, and through washer 22 into slot 15. The end portion 24 of the hinge pin is then turned into notch 19 to prevent longitudinal movement of the pin. In this manner, the washers retain the hinge pin against lateral movement within slots 17 and 18 and the end portion 24 in notch 19 retains the hinge pin against longitudinal motion. As shown in Figure 1, it is preferable to provide two hinge assemblies in the hinged structure, one at each end.

The invention provides, therefore, an improved hinged structure in which a pair of casing sections are held in hinged relation by a simple pin rather than a more complicated form of hinge and which does not require heat sealing or other complicated expedients for retaining the hinge in the sections. The hinge retaining slots in the casing sections of the present invention are shaped to facilitate molding of the sections. In each instance, the

hinged relation between the sections is established by means of a simple metal rod or pin which is bent over at one end and retained in the manner taught herein to prevent longitudinal motion, and a pair of washers is disposed on the pin which functions as bearings and retainers for the assembly.

While a particular embodiment of the invention has been shown and described, modifications may be made and it is intended in the appended claims to cover all such modifications as fall within the true spirit and scope of the invention.

I claim:

1. A hinged structure including in combination, a first section having a top and a plurality of sides extending perpendicularly therefrom, one of said sides terminating in an edge having an elongated notch formed therein and extending along said edge, and said edge having a pair of U-shaped protuberances respectively disposed at the ends of said notch each extending outwardly from said one of said sides substantially perpendicularly thereto and rearwardly from said one of said sides substantially perpendicularly thereto and rearwardly from said edge, with said protuberances defining a pair of aligned slots extending parallel to said edge and facing rearwardly from said edge, and said edge having a further notch therein adjacent one of said pair of slots at the end thereof remote from said elongated notch, a second section having a top and a plurality of sides extending perpendicularly therefrom, one of said sides of said section terminating in an edge having an elongated U-shaped protruding portion formed therein extending along such edge and outwardly therefrom substantially in the plane of said last-named one of said sides, with said protruding portion being disposed in said elongated notch in said first section, said protruding portion defining a slot extending parallel to said last-mentioned edge and facing rearwardly from such edge with said last named slot being aligned with the aforesaid pair of slots, a hinge pin extending through said pair of slots in said first section and through said slot in said second section for maintaining said sections in hinged relation, a pair of washers mounted on said pin respectively adjacent the facing ends of said pair of slots and bearing against the side of said elongated notch for maintaining said hinge pin in said pair of slots and for forming bearing surfaces for said first and second sections, and said hinge pin having a hooked end portion extending beyond the aforesaid one of said pair of slots and disposed in the aforesaid further notch to prevent longitudinal movement of said pin.

2. A hinged structure including in combination, a first molded section having a top and a plurality of integral sides extending perpendicularly therefrom, one of said sides terminating in an edge having an elongated notch formed therein and extending along said edge, and said edge having a pair of molded integral U-shaped protuberances respectively disposed at the ends of said notch each extending outwardly from said one of said sides substantially perpendicularly thereto and rearwardly from said edge, with said protuberances defining a pair of aligned slots extending parallel to said edge and facing away from said edge, and said edge having a further notch therein adjacent one of said pair of slots at the end thereof remote from said elongated notch, a second molded section having a top and a plurality of integral sides extending perpendicularly therefrom, one of said sides of said section terminating in an edge having a molded integral U-shaped protruding portion formed therein extending along such edge and outwardly therefrom substantially in the plane of said last named one of said sides, with said protruding portion being disposed in said elongated notch in said first section, said protruding portion defining a slot extending parallel to said last-mentioned edge and facing away from such edge with said last named slot being aligned with the aforesaid pair of slots, a hinge pin extending through said pair of slots in said first section and through said slot in said second section for maintaining said sections in hinged relation, a pair of washers mounted on said pin respectively adjacent the facing ends of said pair of slots and bearing against the side of said elongated notch for maintaining said hinge pin in said pair of slots and for forming bearing surfaces for said first and second sections, and said hinge pin having a bent-over end portion extending beyond the aforesaid one of said pair of slots and disposed in the aforesaid further notch to prevent longitudinal movement of said pin.
